MATCH PACKAGE HOLDER

Philip J. Schoenberger, St. Paul, Minn.

Application October 8, 1956, Serial No. 614,609

1 Claim. (Cl. 206—38)

This invention relates to an improvement in match package folder and deals particularly with a folder of paperboard for containing a package of matches and which may be used as an ash tray or ash receptacle when such an item is not otherwise readily available.

Cigarette smokers are occasionally embarrassed by having no ash tray readily available while they are smoking. For example, on entering an office or home with a lighted cigarette there is sometimes no ash tray readily available into which the ashes and the unsmoked portion of the cigarette may be inserted. The present device comprises a folder which contains an ordinary package of matches and which may serve as a receptacle for the ashes and the unsmoked portion of the cigarette in such an emergency. As a later time, the folder may be reopened and the ashes and remainder of the cigarette may be emptied so that the folder may be reused.

A feature of the present invention resides in the provision of a paperboard folder which contains a pocket for holding a package of matches and which contains a larger pocket into which ashes may be inserted. This larger package is so arranged that by squeezing together the sides of the folder, the pocket will open to receive the ashes and the remainder of a cigarette.

A feature of the present invention resides in the fact that the folder may be thoroughly cleaned after use. Ordinarily, it is only necessary in emptying the folder to open the ash receiving pocket and to hold the folder in an inverted position so that the contents may fall from place. However, if it is desired to thoroughly clean the folder, the match package can be removed and the entire folder can be unfolded and wiped clean.

A feature of the present invention lies in the fact that the folder may be readily assembled without the use of interlocking locks which are difficult to fasten. The construction is such that the entire folder may be easily locked in assembled position by the insertion of a panel into the smaller pocket designed for accommodation of the match package. When this tongue has been withdrawn from the smaller pocket, the entire folder may be folded into a flat sheet.

A feature of the present invention resides in the fact that the match package may be conveniently used while still contained in the folder, and the strip of material used for igniting the match is readily accessible for use at all times. The match package can be easily removed and replaced and the folder may be reused for a considerable period of time depending upon the material of which the folder is formed.

A further feature of the present invention resides in the fact that the folder may, if desired, be produced of paperboard to which a thin layer of metal foil is laminated. This material is easy to clean and any heat issuing from the ashes or from the unburnt portion of the cigarette may be distributed in such a manner as to prevent any accidental igniting of the matches.

A further feature of the present invention resides in the provision of a folder including two pockets, one of

2

which is designed to contain the match package and the other of which is designed to receive ashes and the like. The cover of the match package protects the matches from being accidentally ignited when the ash receiving pocket is used.

These and other objects and novel features of the present invention will be more clearly and fully set forth in the following specification and claim.

In the drawings forming a part of the specification:

10 Figure 1 is a perspective view of the folder in condition to receive ashes.

Figure 2 is a perspective view of the folder in completely closed position.

15 Figure 3 is a diagrammatic view of the blank from which the folder is formed.

Figure 4 is a plan view of the blank partially folded form.

Figure 5 is a plan view of the folder at the completion of the next folding operation.

20 Figure 6 is a sectional view on the line 6—6 of Figure 5.

Figure 7 is a sectional view on the line 7—7 of Figure 5.

25 Figure 8 is a plan view of a modified form of construction.

The folder is indicated in general by the letter A. The folder, when completed, includes a first pocket 10 designed to receive a match package 11 of common construction. The folder also includes a larger pocket 12 designed to receive ashes and the like.

30 As indicated in Figure 3 of the drawings, the folder includes a back panel 13 which is centrally divided by a fold line 14. A top panel 15 is foldably connected to the upper edge of the rear panel 13 along a fold line 16. A front cover panel 17 is foldably connected to the top panel 15 along a fold line 19.

35 The lower edge of the back panel 13 is connected along a line of fold 20 to a narrow bottom 21. This bottom panel 21 is connected by the fold line 22 to the front panel 23 of the pocket 10. This panel 23 is connected along a fold line 24 to a flange 25. The flange 25 merely serves the purpose of simplifying the operation of closing the folder as will be later described.

40 The rear panel 13 is foldably connected along a side edge 26 to a flap 27. The other side of the rear panel 13 is foldably connected along a fold line 29 to the front panel 30 of the larger pocket 12. This panel 30 is provided with a central vertical line of fold 31 to simplify the expansion or opening of the pocket 12.

45 A tongue 32 is foldably connected to the upper edge of the panel 30 along a fold line 33. This tongue 32 is designed to extend into the smaller match receiving pocket to hold the folder assembled as will later be obvious.

50 55 A flap or flange 34 is hingedly connected along a fold line 35 to one edge of the panel 23 and a flap or flange 36 is hingedly connected along the fold line 37 to the opposite edge thereof. A transverse slot 39 is provided in the front panel 23 of the smaller pocket 10, this slot being provided to permit the portion of the match package against which the head of the match is struck to light to project therethrough.

60 65 As indicated in Figure 3, the fold lines 14 and 31 dividing the panels 13 and 30 forming the rear and front of the larger pocket 12 may extend upwardly into the panels 15 and 32 if desired. These fold lines merely define a place for the panels 13 and 30 to fold when pressure is exerted to open the pocket 12.

70 75 The folder A is assembled as indicated in Figures 4 through 7 of the drawings. The folder is first folded along the aligned fold lines 29 and 37 so that the flap

36 overlies the panel 23 and the panel 30 overlies the panel 13. In this position, the tongue 32 also overlies the top panel 15 and front panel 17.

The folder is next folded along the aligned fold lines 26 and 35 so that the flanges 27 and 34 overlie the panel 30 and flange 36. When the folder has been folded to this extent, it appears as indicated in Figure 4 of the drawings.

The next step of assembly is to fold the folder along the fold lines 20 and 22 so that the portion of the folder shown beneath these fold lines is folded to overlie the flange 27 and panel 30. When in this position, the tongue 32 is inserted in the pocket formed between the panel 23 and the flange 36. The tongue 32 prevents the unfolding of the lower portion of the folder and also prevents the flange 27 and panel 30 from unfolding by overlying these parts.

When the folder has thus been folded, it appears as indicated in Figures 5, 6 and 7 of the drawings. The match package 11 may then be inserted into the pocket 10, the lower portion of the match package being positioned between the tongue 32 and the front pocket panel 23 and its flange 25. Before insertion into the pocket 10, the strip 40 of the match package is pulled loose from the bases of the matches contained. By inserting the package of matches to the full depth of the pocket 10, the upper edge of this strip 40, bearing material useful in igniting the matches, registers with the slot 39 and by slightly raising the match package, the strip 40 will extend through the slot 39 where it is continually accessible for use.

When the folder is not in use, the front panel 17 is tucked into the pocket 10 forwardly of the match package 11 and between this match package and the flange 25 and the front pocket panel 23. In use, the front panel 17 is first removed and the match cover may then be removed to expose the matches. Thus the match package can be used in the conventional way. However, when the folder is to be used in receiving ashes, pressure is applied to opposite sides of the panels 13 and 30. This causes these panels to bow outwardly intermediate their sides, the rear panel 13 bowing rearwardly and the panel 30 bowing forwardly. Thus a pocket is formed capable of receiving ashes and the unburnt portion of the cigarette. When the pressure is released, the pocket automatically closes to enclose the contents.

When it is desired to empty the pocket 12, it is only necessary to apply pressure to expand the pocket and to invert the package so that the contents will fall out. There is normally sufficient friction to hold the match package 11 in place during this operation and the retention of the match package is also insured when the flap 40 is inserted through the slot 39.

Figure 8 of the drawings shows a slight modification.

This construction is identical to the previously described construction with the exception of the front pocket forming panel 41 which corresponds to the panel 23 of the previously described construction. In the arrangement shown in Figure 8, an aperture 42 is provided in this front panel 23 which is of sufficient size to expose the strip of match igniting material thus slightly simplifying the insertion and removal of the match package.

The folder may be formed of any suitable material but preferably comprises a glossy surface paperboard or a paperboard having laminations of metal foil secured to at least one surface thereof. In the event the ashes or cigarette remnant which is inserted into the pocket 12 are hot, the package surface which is high in heat conductivity will distribute the heat sufficiently to permit the folder to be used without danger of igniting the paperboard or the matches.

In accordance with the patent statutes, I have described the principles of construction and operation of my improvement in match package folder, and while I have endeavored to set forth the best embodiment thereof, I desire to have it understood that changes may be made within the scope of the following claim without departing from the spirit of my invention.

I claim:

A match package including a folder of sheet material designed to enclose a match package, the folder including a rear panel, a front pocket forming panel hingedly secured to an edge of said rear panel, flanges hingedly secured to opposite sides of said front pocket forming panel and folded between said front panel and said rear panel in overlapping relation to form a first pocket, flanges hingedly connected to the sides of said rear panel and folded into overlapping relation between said first pocket and said rear panel to form a second pocket, said front panel being substantially shorter than said rear panel, a match folder in said first pocket, a tongue foldably connected to one of said flanges connected to said rear panel and folded between said one flange and said front panel and extending into said first pocket, said front panel having a slot therein substantially the width of said match package and said slot having a portion of the match folder extending therethrough.
